15 Claims. (Cl. 179—27)

This invention relates to telephone systems and more particularly, though not exclusively, to equipment for use in setting up long-distance or toll connections.

5 The nature of the invention will be understood from the following description of certain embodiments thereof.

It is intended to provide a combined line and recording (C. L. R.) toll service entirely without 10 plugs and cords. Each position is equipped with links having talking and monitoring keys and supervisory lamps, but the usual plugs are replaced by automatic switching apparatus. The switching apparatus can be controlled either by 15 dials on the operator's positions or by key sender equipment. Access is provided by means of the automatic switches to all toll routes, to the local exchange equipment, and to miscellaneous circuits such as test desk information and enquiry 20 positions, etc.

Types of positions

There are two principal types of positions, namely inward and outward. The link circuits of the inward positions are connected at one end 25 to trunk line finders which can search for and pick up incoming calls, and at the other end to toll first selectors which are the first switches in the automatic switch train giving access to the various toll routes and the local exchanges. Each 30 operator has up to fifteen inward links on her position, each one having a listening key and monitoring key, calling and called supervisory lamps, and a busy lamp. The associated position circuit contains the various keys required to 35 control the completion and supervision of the connection, including keys for ringing both ways, splitting and releasing either way, together with the digit keys required to control the key senders.

40 The outward positions are arranged to provide C. L. R. outward services, and also to act as toll or point-to-point positions. They are fitted with two types of link circuits; the first is connected to a finder at one end, which searches for 45 incoming calls on the record circuits, and at the other end to a toll first selector; while the second kind of link is connected at both ends to toll first selectors via selector finders which are introduced to cut down the number of first selectors required.

50 The C. L. R. links have a special feature whereby the first level of the finder is connected, not to incoming record circuits, but to toll first selectors. Normally, the finder will not search over this level but can be made to do so under control of a key 55 in the operator's position circuit so that, when

required, the link may be used for point-to-point work, or for the establishment of delayed calls. It is likely that this facility will be of considerable use in enabling the operator to release the calling side of the link and reverse the call should the 5 calling party for any reason have become disconnected during the time in which the operator has been waiting for the forward connection.

Method of operation

Apart from the delayed search facility described later on, the method of operation on various classes of call is as follows:

(A). *Inward calls*.—An inward call arriving on a toll line circuit establishes a calling condition to 15 the allotters which control the movement of the trunk line finders. These allotters will select a suitable link circuit for handling the call, and will cause the associated finder to search for and seize the toll line circuit. The principle of distribution governing the movement of the allotters is that 20 calls shall be distributed to the various positions in rotation, except in so far as this is rendered impossible either by reason of there being no free links on a given position or if the position due to 25 receive the next call is still testing busy owing to the operator not having cleared the sender from the preceding call. This latter condition may, of course, arise if the operator has difficulty in dealing with a call such, for instance, as a personal call in which difficulty is experienced in locating the wanted party.

When the inward link seizes a toll line circuit, a flicker condition is established on the calling supervisory lamp. The operator will answer by 35 throwing her listening key, and this process will cause the sender finder associated with the position to pick up a free sender. At the same time, the link circuit is connected to the operator's position circuit. The operator will ascertain the 40 particulars of the required connection, and will immediately set up the required digits on her key strip. The sender will then transmit the required digits to the automatic selecting equipment, and in the case of a call terminating locally in an 45 automatic exchange, this will actually give connection to the wanted subscriber. In the case of a through call to another toll line, the automatic switchgear will simply select the toll line and the subsequent ringing and supervisory work will be 50 as for standard toll practice.

During the time that the sender is transmitting the required digits, it connects itself direct to the link via a by-path circuit so that the position circuit is rendered available for the monitoring and 55

supervisory work on existing calls, including the clearing of any which have been completed. As long, however, as the sender remains connected to the link, the position is rendered busy to further incoming calls.

To give toll line ringing, subscriber's ringing, or any similar signals, the operator throws the listening key of the required link, and subsequently the appropriate keys of the position circuit. To release an established connection, the link circuit listening key is thrown, followed by the link release key, it being assumed that the normal routine for clearing the toll line to the other operator has previously been carried out. The toll line signal is received as a flicker signal on the supervisory lamp and this flicker condition in the toll line circuit is automatically removed by the throwing of the associated listening key. In order to enable the operator to correct errors, or to re-route calls in cases of difficulty, a forward release key is provided which releases the forward train but not the entire link; the operator may then throw a key to re-introduce the sender and establish the call afresh.

(B). *Outward calls.*—The operating procedure on outward calls is essentially the same except that the operator will be required to perform the customary docketing and timing operations, and will in consequence be unable to handle the same amount of traffic. As a consequence of this, the distribution scheme differs from that for inward calls in that an operator will signify her willingness to accept a call by throwing the key whereupon the allotters will steer the calls to the positions thus indicated. The C. L. R. links are fitted with a device to enable them to be used as point-to-point links and, in consequence, the position is provided with back and front release keys as well as a key to release the entire link. The operator can, therefore, when required, release the finder from a record circuit and by throwing a special key cause the finder to select a toll first selector, and by the use of her key sender can reverse the call to any desired termination.

(C). *Point-to-point calls.*—These are delayed calls built up in accordance with docketing, and they will normally use the double ended links provided for this purpose. The operator will connect her key sender to the back and front ends of the cord in turn, and will establish thereby a connection to the wanted parties or distant operators as the case may be.

Group display lamps

Both classes of positions are provided with a group of lamps to indicate the group or route of the incoming call. These lamps are lighted from an additional bank of the line finder, and in order to avoid excessive splitting of the multiple, this bank is multiplied over a number of positions. This would normally result in confusion between the indications required by the various positions, and to avoid this a flicker indication is given, the various positions being connected in turn, each for a short period. The lighting of these lamps is controlled by the keys on the position, so that the flicker control relays need not operate except when the operator requires the display.

Delayed search

One of the major difficulties in securing efficient working of a C. L. R. toll board is due to the time taken by the operators in making repeated attempts to establish connections on a

congested route. This difficulty is avoided by special arrangements for the group selector circuits which search for a free toll line. The selectors of these circuits are fitted with an additional wiper, the bank contacts associated with which are taken to a group congestion circuit and when a toll line selector arrives at the beginning of a group, before commencing a search it makes a test on this outlet for the special condition from the congestion circuit. If no toll line is available, this condition will not be forthcoming, and the selector will refuse to search, but will issue busy flash to the operator. The operator may now restore her listening key in order to carry on with further calls. The busy flash will stop, but the link busy lamp will remain alight. When a toll line becomes free, the appropriate test condition is restored to the control bank contacts, and this will cause the group selector to transmit a flicker signal to the operator. If she decides to avail herself of the opportunity to complete the connection, she will throw the listening key and this will cause the toll line selector to search over the group and select a free line. Special double test arrangements are made so that in the event of two operators simultaneously attempting to seize the only available junction, only one selector will commence to search and the other will proceed to transmit the flicker waiting signal again. Delayed search may be provided on a non-numerical forwardly hunting switch accessible from a group selector instead of on the group selector itself. The group congestion circuit which controls this operation is arranged for special signaling on both-way routes, so that when calls are waiting on toll line selectors at each end of a both-way group, the congestion circuits will allow them to be released in rotation in a sequence dependent on the time for which calls have been waiting at each end.

Special arrangement of senders

The sender circuits are arranged to accept the necessary code digits for the selection of an outgoing route, and also the numerical digits required for establishing a local connection, or connection to a route which employs through dialing. The sender will normally send the complete storage, but in the event of the toll line selector on an out-dialing call failing to obtain immediate access to a free junction, the sender will release without transmitting the numericals. When the operator, after the delayed search operation, eventually succeeds in obtaining a toll line, she will reset the numericals in the sender, using a dummy code combination which the sender will not retransmit.

Another object of the invention is to provide means to permit a both-way junction to be used in such a manner that the period of delay is maintained approximately equal for calls in each direction. It will be understood that where the number of junctions is relatively small the device will control all the circuits but that in cases where the number of junctions is greater, arrangements can be made to divide the available junctions into three groups, the first operating only in one direction, the second operating in the reverse direction and the third operating in either direction, according to the circumstances of the traffic. In the past it has been the practice for this control to be exercised by the operators at the terminations of the junctions.

On long-distance circuits, for which delay working has to be introduced frequently, it is a

common practice for the operators to pass a number of calls in one direction and then a number of calls in the other direction, without paying particular attention to the waiting load of traffic at either end.

With more recent methods of toll switching it is becoming a practice to indicate to the operator one free junction in each group appearing on her position, and should all junctions be simultaneously in use, the particular one which becomes free first will be immediately indicated at both ends. Furthermore, no provision is made to prevent the same junction being indicated at both ends even when more than one junction is free.

With C. L. R. working, a call is set up directly if a junction is available within, say, thirty seconds, but if a junction is not available in that time, the calling party is asked to hang up and a ticket is made out and passed to a "delayed call" position. In the systems employing call storage, however, it is the practice to encourage the operators to await a circuit becoming free for a longer time, and it will be understood that if there are a number of calls waiting at each end of the junction there is a considerable danger that the junction will be seized at both ends simultaneously and the calls mutilated.

If toll dialing is employed it is important that such collisions should be avoided, and the present invention also provides means to control the direction from which calls should be accepted at the time of congestion. To accomplish this a recording device is associated with each end of a group of junctions and a record is maintained of the product of the number of calls and the delay.

It may happen that if there is a preponderance of calls in one direction, a single call in the reverse direction will have difficulty in being handled in its correct turn. To compensate for this possibility a further feature of this invention provides means whereby after a number of calls in one direction preference is given to a call waiting in the reverse direction, and as the number of successive calls in one direction increases the preference is also increased, tending to reverse direction.

In the accompanying drawings:

Fig. 1 shows the circuit of a non-numerical junction selector adapted for delayed calls;

Fig. 2 shows the circuit of a two-motion junction selector;

Fig. 3 represents, in schematic form, the circuits associated with both ends of a both-way junction group arranged to allot a junction falling idle to the end at which congestion is worse;

Fig. 4 shows the relevant portion of a non-numerical trunk selector, of the kind shown in full in Fig. 1;

Fig. 5 shows a direction delay recorder, associated in multiple with all non-numerical trunk selectors of a group;

Fig. 6 represents a delay counter circuit, associated with all the direction delay recorders;

Fig. 7 represents a both-way trunk line circuit accessible from the trunk selector;

Fig. 8 is an association circuit for connecting together a direction delay recorder and a trunk line circuit as the latter becomes free;

Fig. 9 is a direction compensator and is individual to the direction delay recorder of Fig. 5.

Fig. 1 shows a non-numerical switch, the searching operation of which is in part controlled by an operator. The circuit is taken into use from the bank contacts of a selector level

and on seizure the negative and positive wires *a* and *b* are looped causing the operation of relay A. Relay A closes a possible circuit for the relay P leading to a wiper, the bank contact of which, in the home position, is connected to a source of battery potential if any of the outlets from the switch are available. This source of potential is sufficient to cause the operation of relay P which is a relay of the two-winding type and which is adapted to short-circuit one winding on its operation in order to reduce the potential on the bank contact after operation. Relay A also closes a circuit for relay C which also has two windings, one of which is normally short-circuited, in which circumstances the relay C is slow to operate. If the relay P does operate it will open the circuit of relay C and close the circuit of relay L, which will lock over its own make-before-break contacts. Relay L closes the driving circuit for the switch from ground connected to the bank contacts and the switch will continue to run through its interrupter contacts until it reaches an outlet not marked busy. At this point the relay K operates in series with the rotary magnet and switches the incoming leads through to the outlet. The relay K is maintained operated on the third wire. If all the outlets are engaged the relay P fails to operate and the relay C operates, connecting a flashing signal from lead FL to the fourth wire *d* which will cause a supervisory lamp at the operator's position to flash intermittently. Relay C also connects the high resistance relay HR in series with relay P to the group control wiper so that when source of potential is connected, indicating that one of the outlets has become free, the relay HR only will operate. Relay HR in operating removes the flash from the *d* wire which is now connected to a flicker signal in series with the second winding of relay C back to the operator. The original operating circuit of relay C is now switched over to an interrupted battery which is so timed in relation to the flicker signal that the relay is alternately maintained operated over one winding and then the other. When the operator wishes to commence the searching operation, the circuit over the fourth wire is opened, causing relay C to release. The low resistance circuit for relay P is reconnected and when the relay P operates the switch hunts as already described. If two operators attempt to take a free outlet simultaneously only one P relay will operate, but in the other circuit relay HR will release, relay C will reoperate and flashing signal will be reconnected to the *d* wire. When a further outlet becomes free the relay HR will operate again and the operator can make a further attempt in response to flicker.

Fig. 2 shows the circuit of a two-motion selector which is arranged to be set by either one or two digits according as the group required fills a level or uses only part of a level. Relay C, not shown, is arranged in the normal manner to operate with each impulse. This relay is slow to release and controls the release relay CC which is also slow to release. When relay C releases at the end of the first (or second) digit a circuit is closed through the operating contacts of relay CC to the congestion relay P and if the relay P operates to battery via the group congestion circuit GCC, the drive circuit of the rotary magnet RM, in series with left-hand winding of relay CC, is completed via wiper *w* to earth on all the contacts of the group except the last and selection of an idle outlet takes place in known

manner. When the switching relay H (not shown) operates its contacts $h1$ switch through lead d . If the relay P fails to operate before the relay CC releases, the circuit will be completed 5 for the relay BF through the contacts $sc2$, $hr2$, $c1$, $p1$, $cc1$ to earth. Relay BF connects the flashing lead FLA to the relay FL which in turn connects the relay SC intermittently to the fourth wire, thereby giving a flashing signal to the operator. When the operator restores her listening 10 key, relay SC operates and locks, releasing BF so that busy flash is removed. Relay CC, in its normal position, also closes the circuit for the high resistance relay HR to the group control 15 contact in series with P. When an outlet becomes free relay HR alone operates and switches over the circuit FL at $hr1$ to the flicker ground via $FL1$ thereby causing a quicker train of impulses to be sent back over the fourth wire to flicker 20 the operator's lamp. During these interruptions the circuit for the relay SC is maintained operated over its locking circuit. When the operator wishes the switch to attempt a search, the circuit of the relay SC is opened or high resistance 25 $R1$ is inserted therein by throwing the listening key and the relay SC recloses the circuit for the relay BF. With both BF and HR operated, the relay CC reoperates via $hr5$, $bf3$ and allows a further test to be made by the relay P. The circuit of 30 the relay HR is opened by the relay CC and if relay P fails to operate before CC also releases, the flashing signal is reintroduced as already described.

Referring now to Fig. 3, which represents the 35 equipment at both ends of a both-way junction group, an operator setting up a call in a wanted direction, is connected via a group selector GS to a non-numerical trunk selector TS, which is of the kind shown in Fig. 1 and is adapted to give 40 access to an idle both-way junction circuit JC.

If all the outlets from TS are busy, connection 45 is made to a direction delay recorder DR associated in multiple with all TS circuits giving access to the same group of toll junctions or trunks. Associated with all the DR circuits is a delay 50 counter circuit DLC comprising a switch $R1$ which is stepped round at a given speed whenever congestion conditions exist and has a position individual to each TS circuit. During each revolution of switch $R1$, a switch $R2$ of each DR is 55 given at least one step for each of its associated TS circuits awaiting a free outlet. The number of steps taken by $R2$ in this way is determined by a relay DP individual to DR. The compensator DRC comprises a switch $R5$ which records the number of times those junctions of the group 60 in question, on becoming free, are taken into use consecutively at the far end, and accordingly varies the rate of stepping of a second switch $R3$ of DR for a purpose which will be explained shortly. The circuits JC of a group are adapted 65 to be individually connected to the corresponding DR by an associated circuit AC. This connection is automatically made each time a junction falls free irrespective of the existence of congestion conditions in the group. Each JC comprises a switch $R4$.

When a junction falls free, the JC circuits at 70 both ends are connected to their DR circuits and the switch $R4$ at the outgoing end for the call just terminated is stepped, causing pulses of two different frequencies X, Y to be sent consecutively. On receipt of this signal $R4$, at the incoming 75 end, sends back a pulse of the Y frequency and the outgoing $R4$ returns a further Y pulse.

The incoming and outgoing circuits are now ready to signal the amount of congestion recorded to each other. If calls are waiting at the incoming end, a first "congestion" pulse of Y frequency will be sent, and at the same time, the switch $R3$ of the incoming DR will be stepped forward at least one step. At the outgoing end, on receipt of this pulse, a Y pulse is sent back and the corresponding $R3$ is also stepped. Originally, when no congestion existed, $R2$ and $R3$ of DR 10 were both at normal. $R2$ has been stepped forward over a number of contacts determined by the number of TS circuits of the group awaiting a free junction, and by the length of time these TS circuits have been in the waiting condition. $R1$ takes one step per half-second and is a fifty-point switch, and therefore $R2$ has taken one step per waiting TS every twenty-five seconds. 15

$R3$, when stepped as JC sends a Y "congestion" pulse, takes at least one step to catch up with $R2$. $R3$ takes four steps per Y congestion pulse normally, but is controlled by DRC to take only two steps or one step if the other exchange has taken the last two, or three, junctions falling free respectively. 20

The incoming and outgoing ends continue to exchange Y pulses until switch $R3$ at one end catches up with its $R2$, when no more Y pulses will be sent from that end, and the other end still having congestion recorded, and receiving no further Y pulse, allows the TS circuits to flicker 30 the operators to inform them that a junction is available.

Congestion records at both ends will then be 35 built up again.

It will be seen that the end which has not taken the last two or more junctions, counts off its congestion record by means of switch $R3$ at a much slower rate than the other end, and therefore is more likely to get an available junction. DRC 40 of course allows switch $R3$ to resume its normal stepping rate after a junction has been taken from that end.

If no congestion is recorded at the outgoing end, the return Y pulse therefrom, before congestion signaling begins, is replaced by an X pulse, in response to which the incoming end takes the junction immediately. 45

Referring now to Fig. 4, only a small portion of the non-numerical trunk selector previously described with reference to Fig. 1 is shown. The selector is arranged to pass back a flashing signal to the operator indicating that all the trunk circuits are engaged. Relay C remains operated during the waiting period. Relay HR is connected to a wiper of the switch by C and will operate as soon as a trunk becomes available. The operation of the relay HR will release C. Relay HR removes the flashing signal and substitutes a flicker thereby indicating to the operator that a trunk line is available. The fact that relay C is operated in any one trunk selector circuit indicates that an operator is waiting for a trunk line. It follows that an indication of the traffic waiting in any direction can be obtained by measuring the number of C relays which are operated simultaneously and the time period during which they remain operated. This measurement must be made independently for each direction and the direction delay recorder DR is, therefore, associated only with a group of TS circuits giving access to junctions in one direction only. 60

The actual measurement is controlled by the delay counter Fig. 6 which may be common to a 70 75

number of directions. Detailed operation takes place as follows:

Relay C in the non-numerical trunk selector Fig. 4 connects ground through a decoupling resistance to relay ST of the direction delay recorder, Fig. 5, which in operating closes the obvious circuit for a congestion meter CM indicating the number of occasions on which all trunk lines are engaged. It also closes the obvious circuit for the relay CST of the delay counter Fig. 6.

Relay CST in operating connects the magnet RM₁ of the switch R₁ to a half-second pulse supply causing the wipers of the switch to step forward one step every half second.

Two wipers *rm₁₁*, *rm₁₂* are connected together, one set of bank contacts being connected individually to C contacts of the trunk selectors, the other set of bank contacts being strapped together according to direction and connected to relays DP in the corresponding direction delay recorders, Fig. 5.

Every time the wipers of the switch R₁ pass over contacts corresponding to a trunk selector TS of the group associated with DR, Fig. 5, in the waiting condition, a ground connection will be passed to the relay DP in the delay recorder. Relay DP in operating closes the obvious circuit for magnet RM₂ of the switch R₂, which advances its wipers accordingly.

The switch R₂ has only one level of contacts which are connected to a corresponding set of contacts in the switch R₃, which also forms a part of the direction delay recorder. The switch R₃ is advanced only when a trunk circuit becomes free and it is the function of the switches R₂ and R₃ to count off between them the amount of delay which has been stored since the last trunk circuit became free.

Relay PC which is connected to the wiper *rm₃₁* is arranged to operate when the switches R₃ and R₂ are approximately in phase.

The wipers of the switch R₃ are advanced in stages until the relay PC eventually operates indicating that the switch R₃ has caught up the switch R₂. The number of steps of the switch R₃ comprising the stage may be varied by the compensator, Fig. 9, as described subsequently according to the circumstances.

When a trunk circuit is about to fall free because the call for which it has been used is ended, the release is made dependent upon the direction delay recorder and for this reason the both-way trunk line circuit Fig. 7 must be associated with the recorder. This association is performed by a group of relays K shown in Fig. 8, the connecting function of one of the K relays being shown in Fig. 7.

It will be appreciated that due to the releasing times of relays and the possible differences in exchange voltages the both-way circuit may not tend to become free simultaneously at both ends, and should it happen that two junctions of a group become free at approximately the same time, the associating relays may be caused to operate in such a way that the direction delay recorders at opposite ends become individually connected to different junctions and are unable to signal to one another. In order to avoid confusion arising in this way, one of the two terminations acts slightly different from the other, it being adapted to cancel the first association and make a second association when the conditions indicate that the direction delay recorders have been associated with different trunk lines.

The relays K₁, K₂, K₃, etc., are provided one

per trunk line circuit and one of these relays and its contacts are shown on Fig. 7.

The pairs of terminals AK₁, AK₂; AK₃, AK₄, Figs. 7 and 8, are particular to different junction circuits JC. A potential is connected to terminal AK₁, for instance, when the corresponding trunk line is about to release after completing an outgoing call, and a similar potential is placed on the terminal AK₂ when the same circuit JC is about to release after receiving an incoming call. At one end of the trunk line the terminals AK₁ and AK₂ are connected together, but at the other end they are wired separately in order to avoid cross connections.

When a ground potential is connected to a point such as AK₃, Fig. 8, at the end of an outgoing call, the relay K₂ will operate through contacts *k₁₁*, *k₁₂*, *k₂₁*, *k₂₂*, *kw₁* to battery potential through relay KY. Relay K₂ in operating closes its make-before-break contacts making itself independent of the break contact *k₂₂*. Ground potential now being placed on terminals AK₁ or AK₅ at the termination of other outgoing calls will not cause the operation of the relay K₁ or K₃ because the operating circuit is opened at the contacts *k₂₂*.

When the pairs of terminals AK₁ and AK₂, AK₃ and AK₄, etc. are connected together, and the K relays, Fig. 8, need have no right-hand windings, only one K relay can be operated at a time and this relay will remain operated until the trunk line circuit removes the ground potential.

When the corresponding terminals are not wired together but wired separately, the second terminal is wired through a second winding of the K relay and through a relay KW to the battery potential through relay KY. With this arrangement a K relay can become operated on its second winding even if another K relay is already operated on its first winding. Furthermore, the operation of the relay KW in series with said K relay will open the circuits of the first windings of all K relays so that any K relay, which was previously operated via an outgoing terminal, is caused to release.

The K relay at the "incoming" end of a junction about to come free cannot operate until a signal has been received from the outgoing end after the latter has been connected to its DR. It will be seen that with this arrangement if two trunk lines which have been used in different directions are released simultaneously and both outgoing ends make association with their corresponding direction delay recorders and, in consequence, initiate the releasing signals, a second K relay will be operated over its second winding at the one end to disassociate the delay recorder at that end from the toll line to which it is connected and reassociate it with the toll line which has received an incoming signal.

Turning now to Fig. 7, the relay A is bridged across the conversational leads from the local subscriber and is designed to operate so long as the calling subscriber's receiver is off the hook. The outgoing conversational leads are not shown. Relay A operates B, which is of the slow to release type. Relay C then operates and locks up so that the toll line circuit is not automatically released when the calling subscriber clears.

Considering first the case in which the trunk line circuit is used for an outgoing call. The operation of relay B closes at contacts *b₁* the circuit for the magnet RM₄ of switch R₄ through its interrupter springs, the first bank

contact and wiper *rm41* causing the switch to advance to position 2. The relay SC is operated (via contact *a2* of relay A) on all outgoing calls and the contact *sc1* closes a circuit for magnet RM4; via its interrupter springs, *sc1*, bank contacts, wiper *rm43* to ground. This circuit is maintained until wiper *rm44* reaches its first contacts, which is the twenty-sixth position of the switch. The switch remains in this position during the course of conversation but at the completion of conversation when the relay B releases the circuit for the magnet RM4 is completed through wiper *rm42*, the break contact *b2*, the contacts *g1* and the wiper *rm44* to ground. The switch advances its wipers one step to position 27 in which position ground is connected to the terminal AK1 through contacts *b3*, *rc1*, *sc2* and wiper *rm48*. If the direction delay recorder is not already associated with a trunk line circuit, the relay K will operate and close at contact *k1* the circuit through the wiper *rm42* for the magnet RM4, which advances the switch to position 28. In this position the toll line circuit sends the initial release signal to the distant end. It will be understood that the signaling over the toll line may be carried out in a number of different ways, e. g. by the use of two or more voice frequencies placed on the line or by the use of a single frequency of various duration or by means of direct current signals. In this description it has been assumed that signaling is undertaken by means of two voice frequencies, but the sources of frequencies and their connections to the outgoing junction leads are not shown as they may be of any known type. When the switch R4 reaches position 28, that is, the third position in banks *rm42*, 44, 46 and 48, the circuit is closed for the relay FX through wiper *rm46* contacts *k11*, *sc2*, *rc1*, *b3*. FX in operating connects the X frequency to the outgoing line. In position 28 the magnet RM4 is connected through its interrupter springs and *rm42* to a half-second pulse supply causing the switch to advance one step per pulse to positions 29, 30, 31 and then 32. In positions 28, 29, 30 and 31 relay FX is maintained operated so that as a result the X frequency remains on the line the whole of this period. In positions 32 and 33 the circuit for the relay FX is open, but the circuit for the relay FXY is closed so that in these two positions the Y frequency is connected over the lines. The interrupter circuit for the magnet RM4 is completed wiper *rm42* and the wipers are advanced to position 34. The toll line circuit now awaits a signal from the distant end of Y frequency and when this arrives, frequency-responsive relay Y not shown connects ground through contacts *b3*, *rc1*, *sc2*, *k11*, wiper *rm46*, contact *y1* to the terminal XZ0, which is connected to the direction delay recorder shown in Fig. 5, through one winding of relay XB and the relay Z, which both operate.

Relay Z at *z1* opens a possible circuit for the magnet RM3, and contacts *xb1* close the obvious circuit of the relay X. When the Y pulse terminates, the relays XB and Z are both released. The relay XB is gauged with a heavy spring pressure so that it operates relatively slowly and releases quickly. The relay Z on the other hand has relatively light pressure and operates quickly and releases relatively slowly. During the period between relays XB and Z releasing, a circuit is closed from ground, *z2*, *x1*, *xb2*, to the terminal MAG, which is connected via the cor-

responding terminal of the both-way trunk circuit, through *k2*, and *rm42* to magnet RM4. This signal causes the switch R4 to advance a step and in the following position 35 a circuit is reestablished for the relay FXY which again applies Y pulse over the trunk line. Switch R4 does not remain for any length of time in this position because the circuit is at once closed through the wiper *rm42* which causes the wipers to advance a further step.

In the next position of the switch, the circuit for the relay FXY is maintained until relay X releases and connects ground at *X2* to terminal ZG which is extended through contact *k3* through the bank contact and wiper *rm42* to the magnet RM4 causing the wipers to advance to position 37. In this position the circuit awaits for a further Y pulse from the distant end which, as already described, causes the operation of the relay XB and Z and, at the termination of the Y pulse, ground is connected over the terminal MAG which advances the wipers of the switch R4 to position 38. In this position ground is extended through *rm46*, contacts *pc1*, and terminal XB2 to the second winding of relay XB, Fig. 5, which is operated thereby, and in parallel through the metal rectifier, terminal XB0 and contacts *k4* to relay FXY. The operation of the relay FXY reconnects the Y frequency to the trunk line. The operation of relay XB, which locks up through contacts *xb3* and *z2* to ground, causes the operation of the magnet RM3 through contacts *x3*, *z1* and *xb4*. Relay XB also closes at *xb1* the circuit for relay X which in operating opens the short circuit across the interrupters of RM3 at *x3* and causes the switch to take a step. The switch R3 continues stepping until the circuit is closed for the relay Z through the bank contact and wiper *rm32* and the contacts *x4*.

Relay Z in operating opens the circuit of the magnet RM3, opens at *z2* the holding circuit of the relay XB and closes through the contacts *x1*, *xb2* the circuit for RM4, which is therefore caused to advance through both positions 38 and 39 into position 40.

If the relay PC had been operated when the switch reached position 38, via *st1*, *rm31*, *rm21* to earth, because the switches R2 and R3 were in phase, relays XB and FXY would not have operated, Y pulse would not have been connected to the trunk line and relays CA, Fig. 9, and RC would have been operated via *fry1*, *k5*, *pc1* energized, *rm46* to earth.

Relay RC is arranged to lock over contacts *b2*. Switch R4 returns home through contacts *rc2* and *rm44* to ground. Relay RC indicates that the toll line circuit should receive an incoming call and in consequence does not permit the condition of the group test terminal to be altered.

Assuming that the relay PC is not operated and that the switch R4 was advanced to position 40, the circuit would again await the receipt of Y pulse which again causes the operation of relays XB and Z, and again at the termination of the Y pulse the wipers advance to position 41. If the relay PC is still not operated the relays XB and FXY will be again operated in positions 41 and 42 and the wipers step forward to 70 position 43.

Assuming now that the distant end does not reconnect the Y pulse, the relays XB and Z will not operate but the circuit will be completed from the magnet RM4 through the wiper *rm42*, con-

tact *k2*, terminal MAG, *xb2*, Fig. 5, *x1*, make-before-break contacts *mb1*, left-hand winding of the relay MA to ground.

5 Relay MA being of relatively high resistance, the magnet RM4 will not be operated but the relay MA will operate and close the contacts *ma1* and the half-second pulse supply to the second winding of relay MA and the relay MB. When this supply is connected the relay MB operates 10 and the relay MA remains operated for the duration of the pulse. On the completion of the pulse, relay MB remains operated on its upper winding through contacts *mb1* in series with the magnet RM4, but MA is released. When 15 ground is again connected to the pulse supply the circuit is completed through the contacts *ma1*, *mb2* for the relay MC and if by this time Y pulse has not been received, relay MC operates and connects ground via *mc1*, *st4* to the MCG 20 terminal through contacts *k6*, Fig. 7, to the lower winding of relay SC, which operates. Relay SC closes at *sc3* a locking circuit through *b2*, *rm44* to ground. Contacts *sc4* open the locking circuit of relay C which in releasing closes a homing 25 circuit; RM4, interrupter, *sc1*, *c1*, *rm44*, ground. When the switch reaches home, ground is removed from the terminal AK1, and relay K is released together with the direction delay recorder.

30 It will be understood that the operation of relay SC, indicating that the trunk line should be used for an outgoing call, may take place at position 40, 43, 46, etc. and similarly the operation of the relay RC may take place at position 35 38, 41, 44, etc.

If the trunk line circuit is associated with the direction delay recorder on an outgoing connection and the relay KW becomes operated because the distant end recorder is associated with the 40 different trunk line, a circuit is completed through contacts *k7* and *g2* for the relay G, which is arranged to lock up. The contacts *g1* and subsequently the contacts *g3* and *g4* advance the wipers of the switch R4 through normal to position 45 26 in which position the circuit for the relay G is opened. Relay G in releasing closes the circuit for the magnet RM4 through *rm42*, *b2*, *g1*, *rm44* causing the switch to advance to position 27 when reassociation with the direction delay recorder will take place when the latter circuit 50 becomes available.

Considering now the case of an incoming call, relays B and C of the trunk line circuit are operated and switch RM4 is advanced to position 55 2 but no further since SC is not energized. It remains in this position throughout the conversation but on release a Y pulse is received from the distant end.

Relay Y closes at *y2* the circuit for the magnet RM4 and switch R4 is advanced to position 3. In position 3 ground is connected through wiper *rm41* to terminal AK2 to cause the association with the direction delay recorder to take place. When the Y pulse is completed and the relay K 60 operated, ground is connected through *y3*, *k1* and *rm41* to advance the switch to position 4.

In this position the relay FXY is operated and the return Y pulse is sent to the distant trunk exchange. The wipers are advanced by direct 70 earth on *rm41* to position 6 where a further Y pulse signal is expected from the other exchange and when it is received causes the operation of relay XB and Z, Fig. 5, in the manner already described.

75 In positions 1 and 8 the operation of relay XB

is made dependent on the condition of contacts *pc1* as before so that, in this and subsequent sending positions, the controlling switch R3 is advanced, and as soon as the switch R3 is in phase with the switch R2, no further congestion "Y" 5 pulses are sent.

If no further Y pulse is received from the distant exchange, relays MA, MB and MC are operated as already described. The subsequent operation of relay SC results in the trunk line being 10 made available for an outgoing call. If, on the other hand, relay PC is operated resulting in the operation of relay RC, the trunk line is prepared to receive a call from the distant end.

It may be arranged that if the outgoing end 15 has no calls waiting the second signal sent in positions 35 and 36 will be of X pulse rather than of Y pulse; such an arrangement can be accepted at the incoming end by wiring position 6 to position 9 through the back contact of a relay 20 RX (not shown) responding to the X pulse. It will be arranged that should the X pulse be received in position 6 the relay SC can be operated immediately.

During the period when the trunk line is associated with the direction delay recorder and relay KY is operated, the possible circuit for the switch R2 is opened at contact *kyl* and on this account the circuit for the relay PC cannot be caused to open instantaneously.

Reference has already been made to the fact that in certain circumstances there may be a preponderance of traffic in one direction and in consequence over a relatively long period there will be a large number of waiting calls in one direction. Under these conditions it may be difficult for a call in the reverse direction to get access. In order to eliminate this possibility a compensator circuit is proposed as shown in Fig. 9. It is the purpose of this circuit to vary the 30 connection via the bank contacts associated with the wiper *rm32* so that the size of the stages of movement of said wipers, when sending congestion pulses, is in part dependent upon the direction in which the majority of the traffic is 35 flowing.

As an example, the contacts associated with the wiper *rm32* are divided up into three groups. Contacts 1, 3, 5, 7, 9 etc., are connected together and wired to terminal CX. Contacts 2, 6, 10, 14, etc. are connected together and wired to terminal CY, contacts 4, 8, 12, etc. are likewise connected to terminal CZ, and also direct to the right-hand winding of relay Z.

Relay CA, Fig. 9, is connected in series with 55 the operating winding of relays RC of the various trunk line circuits and every time that a trunk line is released and assigned for an incoming call relay CA will operate. Relay CA closes the obvious circuit for the switch R5 which is 60 caused to take one step for each successive junction assigned for incoming use.

Contacts 3, 4, 5, 6, 7, 8, 9, 10 associated with wiper *rm51* are commoned together and connected to the terminal CZ. Corresponding contacts associated with the wiper *rm52* are connected to terminal CY and contacts 4, 5, 6, 7, 8, 9, 10 associated with wiper *rm53* are connected to the terminal CX.

On the second successive incoming call switch 70 R5 reaches position No. 3 and the terminals CY and CZ are commoned together and because of this the relay Z in the direction delay recorder is operated after only two steps instead of four steps of R3.

- If a further incoming call is received, R5 advances another step and in this position terminals CX, CY and CZ are all commoned together. Relay Z operates after every one step of R3. On the use of any junction in the route for an outgoing call a relay MC (not shown) will operate and complete the circuit through wiper rm54 to drive the switch to a further home position, from whence the process will be repeated.
10. What is claimed is:
1. In a toll switching system, the combination with a plurality of operators' positions of a plurality of link circuits each comprising a finder, an incoming line group available for connection with all of said link circuits, an allotter for operatively associating any link with any position, means responsive to the existence of a calling condition on any line of said incoming line group for operating any idle link to connect its associated finder with said calling line, and means responsive to an operation at any one of said positions for operating said allotter to associate the link extended to the calling line with the position at which said operation has taken place.
  2. In a toll switching system, the combination of two offices connected by a plurality of two-way trunk lines, a selector circuit at each office having access to said trunk lines, means at each office operatively associated with each selector for determining and recording the time interval during which all of said trunk lines are busy, means at each office operatively associated with each selector for determining and recording the time interval during which each of said selectors has been waiting for a free trunk line to establish a call in its own direction, means responsive to a line becoming free for signaling over said line the selector delay at each office, and means for allotting said free line to the office which had the longest selector delay.
  3. In a telephone system, two offices, a group of two-way trunk circuits extending between said offices, switching means at each office for seizing idle trunk circuits, and means at each office controllable in accordance with the number of calls awaiting completion at each office and the aggregate waiting period of such calls for allocating an idle trunk circuit for the use of the office in which the traffic congestion is greater.
  4. In a telephone system, two offices, a group of two-way trunk circuits extending between said offices, switching means at each office for seizing idle trunk circuits, means at each office for recording during periods when no idle trunk circuits are available the aggregate waiting time of calls awaiting an idle trunk circuit, and means at each office controllable jointly by the recording means at both offices for determining which office may use an idle trunk circuit for an outgoing call when it becomes free.
  5. In a telephone system, two offices, a group of two-way trunk circuits extending between said offices, switching means at each office for seizing idle trunk circuits, means at each office for recording during periods when no idle trunk circuits are available the aggregate waiting time of calls awaiting an idle trunk circuit, and means at each office controllable jointly by the recording means at both offices for allocating a trunk circuit when it becomes idle to the use of the office whose recording means indicates the greater traffic congestion.
  6. In a telephone system, two offices, a group of two-way trunk circuits extending between said

offices, switching means at each office for seizing idle trunk circuits, means at each office for recording during periods when no idle trunk circuits are available the aggregate waiting time of calls awaiting an idle trunk circuit, and means at each office controllable jointly by the recording means at both offices responsive to a trunk circuit becoming free for indicating at the office where the greater traffic congestion exists that the free trunk circuit is to be used on an outgoing call and for indicating at the other office that the free trunk circuit is to be reserved for an incoming call.

7. In a telephone system, two offices, a group of two-way trunk circuits extending between said offices, switching means at each office for seizing idle trunk circuits, means at each office for recording during periods when no idle trunk circuit is available the aggregate waiting time of calls awaiting an idle trunk circuit, means at each office operative when a trunk circuit becomes available for transmitting signal impulses to the other office, and means at each office jointly responsive to the recording means of that office and to the impulses received from the other office for allocating said idle trunk circuit for an outgoing call to the use of the office in which the traffic congestion is greater.

8. In a telephone system, two offices, a group of two-way trunk circuits extending between said offices, switching means at each office for seizing idle trunk circuits, means at each office for recording during periods when no idle trunk circuits are available the aggregate waiting time of calls awaiting an idle trunk circuit, means at each office operative when a trunk circuit becomes available for transmitting signal impulses in alternation over said idle trunk circuit to the other office, and means at each office jointly responsive to the recording means of that office and to the impulses received from the other office for allocating said idle trunk circuit for an outgoing call from the office in which the traffic congestion is greater and for an incoming call at the office in which the traffic congestion is less.

9. In a telephone system, two offices, a group of two-way trunk circuits extending between said offices, switching means at each office for seizing idle trunk circuits, a first recording switch at each office, means at each office operable during periods when no idle trunk circuits are available for setting the associated recording switch in accordance with the aggregate waiting time of calls awaiting an idle trunk circuit, a second recording switch at each office, means at each office operative when a trunk circuit becomes free for transmitting signal impulses to the other office for setting the second recording switch at the other office, and means operative when the recording switches of either office are in substantial phase relationship for transmitting a signal to the other office indicative that the free trunk circuit may be used at such office for an outgoing call.

10. In a telephone system, two offices, a group of two-way trunk circuits extending between said offices, switching means at each office for seizing idle trunk circuits, a first recording switch at each office, means at each office operable during periods when no idle trunk circuits are available for setting the associated recording switch in accordance with the aggregate waiting time of calls awaiting an idle trunk circuit, a second recording switch at each office, means at each office operative when a trunk circuit becomes free for transmitting sig-

nal impulses to the other office for advancing the second recording switch at the other office a pre-determined amount in response to each impulse, means operative when the recording switches of either office are in substantial phase relationship for transmitting a signal to the other office indicative that the free trunk circuit may be used at said other office for an outgoing call, and means at each office effective when the other office has been given precedence for a predetermined number of successive outgoing calls for reducing the amount of advancement of the second recording switch thereof in response to impulses from the other office whereby said office is given precedence for completing an outgoing call.

11. In a telephone system, two offices, a group of two-way trunk circuits extending between said offices, switching means at each office for seizing idle trunk circuits, a first recording switch at each office, means at each office operable during periods when no idle trunk circuits are available for setting the associated recording switch in accordance with the aggregate waiting time of calls awaiting an idle trunk circuit, a second recording switch at each office, means at each office operative when a trunk circuit becomes free for transmitting signal impulses to the other office for advancing the second recording switch at the other office a pre-determined amount in response to each impulse, means operative when the recording switches of either office are in substantial phase relationship for transmitting a signal to the other office indicative that the free trunk circuit may be used at said other office for an outgoing call, and means at each office effective in response to the allotment in succession of different predetermined numbers of available trunk circuits to the other office for outgoing calls for successively reducing the amount of advancement of the second recording switch thereof in response to the impulses from the other office whereby said office is given precedence for completing an outgoing call.

12. In a telephone system, two offices, a group of two-way trunk circuits extending between said offices, switching means at each office for seizing idle trunk circuits, traffic congestion recording means in each office, and means in each office operative in response to a trunk circuit becoming available for associating the recording means of each of said offices with the opposite ends of said available trunk circuit.

13. In a telephone system, two offices, a group of two-way trunk circuits extending between said offices, switching means at each office for seizing idle trunk circuits, traffic congestion recording means in each office, and means in each office operative in response to two trunk circuits becoming available substantially simultaneously for associating the recording means of each of said offices with the opposite ends of one of said available trunk circuits.

14. In a telephone system, two offices, a group of two-way trunk circuits extending between said offices, switching means at each office for seizing idle trunk circuits, means at each office for recording during periods when no idle trunk circuit is available the aggregate waiting time of calls awaiting an idle trunk circuit, means at each end of each trunk circuit individual thereto operative when a trunk circuit becomes available for transmitting signal impulses over said trunk circuit to the other office, and means at each office jointly responsive to the recording means of that office and to the impulses received from the other office for allocating said idle trunk circuit for an outgoing call to the use of the office in which the traffic congestion is greater.

15. In a telephone system, two offices, a group of two-way trunk circuits extending between said offices, switching means at each office for seizing idle trunk circuits, a traffic congestion recorder in each office, said recorders each comprising a first recording switch operable during periods when no idle trunk circuits are available for recording the aggregate waiting time of calls awaiting an idle trunk circuit, and a second recording switch, means at each end of each trunk circuit individual thereto and operative when a trunk circuit becomes available for associating the end of said trunk circuit at each office with the traffic congestion recorder thereat and for transmitting signal impulses to the other office for setting the second recording switch at the other office, and means operative when the recording switches of either office are in substantial phase relationship for transmitting a signal to the other office indicative that the free trunk circuit may be used at said other office for an outgoing call.

ESMOND P. G. WRIGHT.
GEORGE C. HARTLEY. 50
